UNITED STATES PATENT OFFICE.

THEODOR HUGO, OF WILMERSDORF, NEAR BERLIN, GERMANY.

FEEDING DEVICE FOR ENVELOPE OR BAG MAKING MACHINES.

Application filed June 4, 1925, Serial No. 34,938, and in Germany April 24, 1925.

This invention relates to an envelope or bag making machine of the type in which a paper ribbon or sheet is continuously fed as from a roll.

5 In order that the advantages of the continuous uniform feed of the ribbon should not be lost by the stop operation necessary in a machine of this kind, according to the present invention only that part of the ribbon is stopped which is immediately in front of the cutting device, while the rest of the ribbon 10 is fed uninterruptedly.

Due to the continuous advance of the ribbon toward the stopping position, a loop is 15 constantly formed in the paper, which must be straightened before the next stamping act. The straightening of the paper loop at the correct time and into the correct feeding plane can only be effected by the elasticity of 20 the paper itself without the aid of mechanical means in the case of strong paper when formed into short loops. In weak papers and more particularly with large loops, the ribbon must be straightened and the cut-off 25 blanks conveyed to the cutting and stamping device by mechanical means essentially comprising a movable supporting plate and feeding rolls which have accelerated movement, and it is in this connection that the present 30 invention has special application.

The accompanying drawings represent a feeding device constructed according to the invention and therein:

Fig. 1 is a central longitudinal sectional view with the loop-supporting plate in normal position.

Fig. 2 is a view similar to Fig. 1 but with said plate in loop-supporting position.

Fig. 3 is a plan of the device.

40 Fig. 4 is a front elevation of the cutting and stamping apparatus.

Fig. 5 is a plan of the latter device showing the presser and a portion of the paper ribbon.

45 Fig. 6 is a fragmentary plan view which shows the cutting and stamping device with the upper blades removed.

Fig. 7 is an enlarged longitudinal sectional detail showing the releasable feed roll mechanism in positions corresponding to Fig. 1, and

50 Fig. 8 is a view of the parts of Fig. 7 in positions corresponding to Fig. 2.

The paper ribbon or sheet 1 as drawn 55 from a roll or otherwise (not shown) is provided with gummed corners 1^a, (Figs. 3, 5

and 6); said sheet is led by rollers 4 and 5 rotatable about pins 2 and 3 over a guide roller 6 and then by feed rolls 7, 8; 9, 10; and 11, 12 and under a pressure 13 in the 60 direction shown by the arrow to the position 14 at which the cutting and stamping devices (Figs. 4-6) are arranged. The pairs of feed rollers 7, 8; 9, 10; and 11, 12 are suitably driven from the machine so that the paper 65 ribbon 1 is fed uninterruptedly at a uniform speed in the direction of the arrow. The feed rollers 8 and 10 are pressed by means of a lever system under the action of springs 70 15 on the rollers 7 or 9, so that the feed is 70 effected uniformly and efficiently.

As soon as the ribbon 1 has been advanced under the presser 13 so that a definite portion has arrived under the cutting and stamping device (Figs. 4-6) at position 14, 75 the presser 13 descends on the ribbon through the action of a two-armed lever 17 rotatable about its pivot 16 and driven by means of a rod 18 from a cam provided on the machine. The feed of that portion of 80 the ribbon which is behind the presser 13 is thus stopped, so that the rest of the ribbon alone is at that moment moving towards the presser. At the moment when presser 13 descends on the ribbon, the roller 85 12, which oscillates about the pivot 20 since it is carried by means of a two-armed lever 19, is raised from the paper by a rod 22 pivoted thereto at 21 and connected with a cam on the machine; the gear wheels 23 on such rollers 11 and 12 remaining in mesh. Since the paper or material is relatively 90 thin, that used for instance being less than a millimeter, a very slight movement of roll 11 away from roll 12 is sufficient to destroy 95 transporting engagement of the rolls with the material, as best shown in Fig. 8. At the same time, said movement is not sufficient to demesh the gear wheels 23. The roller 12 is rotated by sprocket wheels 24 and 25 which are driven from the machine. The roller rotates, therefore, continually in the 100 direction of the feeding movement of the paper and faster than such feeding movement.

The roller 12 tends as soon as it has descended and pressed on the ribbon to draw it tightly in the direction of movement. It cannot, however, feed the paper faster than is allowed by the pairs of feeding rollers 7, 8, 9, and 10. The feeding movement of the roller 12 is aided by the roller 11 which is 105 110

2 mounted below the paper and rotates at the same speed. The pull due to the rollers 11, 12 occurs on the descending engagement of the roller 12 with the paper at the moment in which the presser 13 releases the paper or ribbon, previously held stationary, for further advance in the direction shown by the arrow. At the moment in which the presser 13 descending on the paper holds it stationary, a loop begins to form in the paper (Fig. 2) since the rollers 7, 8, 9 and 10 move the ribbon forward uninterruptedly towards the presser. The loop is guided by means of a supporting plate 27 pivoted at 15 26 which is raised and lowered by means of a system of levers 28-32 under the action of a rod 33 operated by the machine, the paper always lying on the upper surface of the plate 27, the movement transmitted from 20 the rod 33 to the plate 27 taking place exactly at the time in which the loop is being formed and in the same direction. As soon as the loop has been formed, that is, at the end of the halt of that part of the paper 25 which is held under the presser 13, the plate 27 is in its highest position. At this moment which coincides with the end of the cutting and stamping of the portion of the ribbon projecting beyond the presser 13, the latter rises and releases the paper, and allows it to move again in the direction of the arrow. As the roller 12 descends on the ribbon 1 and on the roller 11, the plate 27 30 again returns to the horizontal position (Fig. 1).

At the time of the descent of the plate 27, the roller 12, rotating somewhat faster than the ribbon, straightens and feeds it under the presser 13 towards the cutting devices at the position 14. Thus the paper is taut and always under tension during the formation of the loop and is thereby secured from any kind of displacement or retardation. Also, the cut blanks are always reliably fed towards the stamping and cutting device at the right time, since the movement is positively effected, so that the same length of paper is always stamped and cut off with correctly defined edges.

50 For assisting the tension exerted by the rollers 11 and 12, other pairs of rollers of this type which act in the same manner and are actuated in succession can be arranged in combination with the plate 27, so that their pull comes into action during the descent of the plate 27.

Means other than the descending rollers described above can be employed for straightening the loop. For example, both rollers 60 may be fixed and one roller provided with a portion excised from its circumference, so that, temporarily, the paper ribbon is not advanced by the roller. In this case the rollers need not be lifted.

65 The knives of the locally fixed cutting and

stamping device are disposed so that the upper blades 34 and 38 are reciprocated vertically by means of a transverse member 41 sliding in vertical guides 39, 40 and actuated by a lower transverse member 42 which 70 is operated from the machine by a rod 43. The upper blades slide against correspondingly formed stationary lower blades 44. The accurate sliding of the upper blades relatively to the lower blades is obtained by 75 guiding the upper knife in vertical slides 45-48 as shown in Fig. 5. In Fig. 6 the vertical guides 39 and 40 for the upper knives and the stamping device are shown with the cutting edge 34 and the parts 35-38 80 to be stamped out, the upper member 41 being removed. The part 49 in the line of the cutting edge of the blade 34 is cut off at the same time by the blade 34 which is provided with a correspondingly formed punch. 85

I claim:

1. A machine of the class described, comprising means to feed material, means to periodically arrest the feed of the material past one position in its path of travel whereby continued feeding in the rear of said position will form loops in the material, movable elongated supporting means to engage and follow the loop-forming portions of the material during the forming and receding of the loops, and means to feed the loops at an accelerated rate during the intervals of release of the material by the first-mentioned means. 100

2. A machine of the class described, comprising means to feed material, means to periodically arrest the feed of the material past one position in its path of travel whereby continued feeding in the rear of said position will form loops in the material, a plate 105 of a length to support the loops throughout, means to move said plate, said plate being adapted to engage and follow the loop-forming portions of the material during the forming and receding of the loops, and means to feed the loops at an accelerated rate during the intervals of release of the material by the first-mentioned means. 110

3. A machine of the class described, comprising means to feed material, means to periodically arrest the feed of the material past one position in its path of travel whereby continued feeding in the rear of said position will form loops in the material, a plate 115 below the material of a length to support the loops throughout, means to rock said plate, said plate being adapted to engage and follow the loop-forming portions of the material during the forming and receding of the loops, and means to feed the loops at an accelerated rate during the intervals of release of the material by the first-mentioned means. 120

4. A machine of the class described, comprising means to feed material having rollers on opposite sides of the material, means 125

to drive said rollers at an accelerated rate, means to periodically arrest the feed of the material past one position in its path of travel whereby continued feeding in the rear 5 of said position will form loops in the material, supporting means to engage and follow the loop-forming portions of the material during the forming and receding of the loops, and means operable to release said roll- ers from transporting engagement with the 10 material during the forming of the loops and reestablish such engagement after formation of the loops and release thereof so that the accelerated motion will cause the loops to rapidly recede and be fed past said position. 15

In testimony whereof I have affixed my signature.

THEODOR HUGO.
